UNITED STATES PATENT OFFICE

CHARLES L. FOWLE, OF DOWAGIAC, MICHIGAN.

GRAIN-DRILL.

1,074,784.

Specification of Letters Patent.

Patented Oct. 7, 1913.

Application filed March 25, 1911. Serial No. 616,898.

To all whom it may concern:

Be it known that I, CHARLES L. FOWLE, a citizen of the United States, residing at Dowagiac, Michigan, have invented certain new and useful Improvements in Grain-Drills, of which the following is a specification.

This invention relates to improvements in grain drills, the improvements being especially well adapted to shoe grain drills, although some of the features are applicable to grain drills having other styles of furrow openers, as, for instance, of the disk type.

15 The objects of this invention are: First, to provide an improved construction of shoe furrow openers and spring devices. Second, to provide a special connection for the chain coverers in such a device. Third, 20 to provide in conjunction with spring pressure devices for grain drills, improved spring counterbalance means, which, when the shoes are thrown down, serves to assist in urging the same into the ground, and also 25 to assist the operator in elevating the sections of shoes. Fourth, to provide in a shoe grain drill, particularly, an improved construction of boot which especially coats with the rod and spring structure, affording 30 great security for the engagement of the rod springs at the top and a smooth surface over which the same plays in use.

35 Objects pertaining to details and economies of construction, will definitely appear from the description to follow.

I accomplish the objects of my invention by the devices and means described in the following specification.

The invention is clearly defined and 40 pointed out in the claim.

The portions of a grain drill necessary to a clear understanding of my invention in its preferred embodiment are illustrated in the accompanying drawing, forming a part of 45 this specification, in which:

Figure I is a detail perspective view of a part of a shoe grain drill with my improvements in place. Fig. II is a detail perspective view of one of the end shoes showing the position of the same when the pressure is applied. Fig. III is an enlarged detail 50 central sectional view from front to rear, through the grain drill shoe and boot illustrated in Figs. I and III, embodying the 55 features of my invention, showing the method of constructing the boot and se-

curing the same to the shoe. Fig. IV is an enlarged detail sectional view on lines 4—4 of Fig. III, showing further in detail the method of detachably securing the shoe to the boot. Fig. V is an enlarged detail sectional view on lines 5—5 of Fig. III, showing the method of securing the flange to the boot. Fig. VI is a detail view showing the adjustable spring feature for facilitating 65 the operation of the pressure control. Fig. VII shows the coverer features of my invention and the counter-balance as applied to a disk grain drill in which coiled springs are usually made use of for applying the pres- 70

In the drawing, the sectional views are taken looking in the direction of the little arrows at the ends of the section lines, and similar numerals of reference refer to similar parts throughout the several views.

Considering the numerals of reference, the sides 1 of the frame of the drill are of angle bars and are secured to the cross beam 3 to which the shoe draw bars are connected. 80 The carrying wheels 2 are in the usual position. The rock-shaft 4 is at the rear of the machine for applying pressure to the shoes or furrow openers, and to elevate the same. The beam 3 is located above the axle, and the 85 shoes 5 are each connected to a pair of draw bars 6 by means of rivets 7, the draw bars being each pivoted at 8 to a hanger 9. A spreader 28 is between the upper portion of each pair of draw bars, over which the 90 springs 27 act.

The shoe is made up of a pair of steel plates 10, welded together at the bottom, forming an opening at the upper side into which a cast boot-block 11 is secured, the 95 same being flanged at 12 to fit on the upper edge of the shoe plates. This boot-block is retained in place by the pivoted bolt 13 having an eye 15, which swings on the transverse pivot pin 14 disposed through the 100 shoe plates 10. The bolt 13 extends upwardly through the boot-block and is provided with a screw nut 16. This boot-block 11 is provided with a downwardly-projecting guard 18, and has a conduit there-through which is a continuation of the boot conduit.

The sheet metal boot 19 is secured by rivets 20 to the upper part of the boot-block and delivers into the conduit 17. A broad 110 washer-like flange 21 is at the upper end of the boot 19 and is retained in place by

outwardly-projecting lugs 23 beneath the same, and a projecting rib 22 upset above the same, thus making a very smooth boot, with a very broad flange at the top for engaging the rod springs.

Back of the boot-block 11 is a loop 24, to which the chain coverers 26 are connected. These coverers next to the wheels at each side of the grain drill are provided with 10 long arms or links 25 carrying the covering chains 26 at their rear ends.

The rod springs 27 are of the usual construction for a shoe grain drill of this kind, and engage over the spreader 28 and terminate in suitable hooks 29 which engage the upper sides of the draw bars 6, there being 15 a pair for each furrow opener.

Rock shaft arms 30 are secured to the rock shaft 4 by suitable bolts 31, and are connected by the forked links 32 to the rear ends of the springs 27 by the outwardly-projecting pivots 33, 33. A chain 34 connects the rear end of one of the springs 27 to the rearwardly-projecting rigid arms 25, and is 25 of such length that when the rock shaft 4 is rotated to elevate the shoes, it will lift the link or arm 25 upwardly, carrying the covering chain 26 free from the ground during the turning of the grain drill. This avoids 30 catching the covering chains under the carrying wheels 2, which frequently results in breakage, and always interferes with the effective operation of the machine in starting.

To facilitate the manipulation of the rock shaft 4, I provide an arm 38 on the same, which swings below the horizontal when pressure is applied to the shoes by this rock shaft, and which swings above the horizontal when the furrow openers are elevated 35 by the rock shaft.

A forwardly-projecting pitman 36 is pivoted at 37 to this rock shaft arm and extends through the perforated plate 39 on the beam 3. I interpose a strong coiled spring 45 35 between the plate 39 and the head of the bolt-like pitman 36. It will be seen that when this arm 38 is exactly horizontal, the spring has no tendency to rotate the rock shaft 4. When, however, the rock shaft 4 is so adjusted that the arm 38 drops below the horizontal, as it does when pressure is 50 applied to the shaft, the spring 35, by its tension, tends to throw the arm downwardly

and thereby assists the application of pressure to the shoes. When the arm 38 is 55 thrown above the horizontal, when elevating the furrow opener, the spring 35 exerts pressure upon the same to assist the operator in raising the shoes from the ground.

It will thus be seen that the operator, by 60 means of this device, is greatly assisted in elevating the shoes, and that the spring does not interfere with the effective application of pressure to the shoes or other furrow openers, but assists in the same. 65

I have thus described my invention as applied to shoe grain drills.

In Fig. VII I show my improvements applied to a grain drill with disk furrow openers. In this structure, the arms 25 are 70 pivoted to the back of the boots of the disk furrow openers. The covering chains 26 are on the ends of the arms 25 and are elevated from the ground when the furrow openers are raised, and are clear from engagement with the carrying wheel of the grain drill exactly as in the other device. The chains 34 are connected to the arms 25 and to the arms on the rear rock shaft. This pressure device is also assisted by the identical spring structure illustrated and described in connection with the pressure rock shaft of the shoe drill construction. 75 80

Having thus described my invention, what I claim as new and desire to secure by Letters Patent is: 85

In a grain drill, the combination of the frame, carrying wheels therefor, furrow openers, pressure controlled devices for the said furrow openers, chain furrow coverers 90 at the rear thereof with rearwardly-projecting arms pivoted on the boots to carry said chain furrow coverers; flexible connections from the said pressure controlled devices to the rearwardly-projecting arms whereby, 95 when the pressure is relieved and the furrow openers are raised, the chain furrow coverers will be elevated above the ground by said flexible connection, as specified.

In witness whereof, I have hereunto set 100 my hand and seal in the presence of two witnesses.
